United States Patent

Des. 236,939
Patented Sept. 30, 1975

236,939

FERTILIZER APPLICATOR

Alfred J. Piel, Hubbard, Iowa 50122

Filed Nov. 11, 1974, Ser. No. 522,638

Term of patent 14 years

Int. Cl. D8—05

U.S. Cl. D8—2

Fig. 1

Fig. 2

Fig. 3

Fig. 4

Fig. 5

Fig. 6

FIG. 1 is a perspective view of a fertilizer applicator showing my new design;

FIG. 2 is a side elevational view thereof;

FIG. 3 is a side elevational view thereof as seen from the left-hand side of FIG. 2;

FIG. 4 is a side elevational view thereof as seen from the right-hand side of FIG. 2;

FIG. 5 is a top plan view thereof; and

FIG. 6 is a bottom plan view thereof.

I claim:

The ornamental design of a fertilizer applicator, substantially as shown.
